UNITED STATES PATENT OFFICE.

GEORGE LANCE, OF PONDEREY, IDAHO.

RAIL-JOINT.

1,273,505.

Specification of Letters Patent. Patented July 23, 1918.

Application filed November 26, 1917. Serial No. 204,042.

To all whom it may concern:

Be it known that I, GEORGE LANCE, a citizen of the United States, residing at Ponderay, in the county of Bonner and State of Idaho, have invented certain new and useful Improvements in Rail-Joints, of which the following is a specification.

The present invention relates to improvements in rail joints and is designed for the purpose of providing an efficient means for supporting the rail ends with respect to the ties, for supporting them against horizontal movement and to provide an effective jointing whereby the weight of the traffic will be removed from the rail ends and transferred to the plate during the passage of such traffic over the rail ends.

The primary object of the invention is the provision of a comparatively inexpensive and efficient rail joint especially adapted for use in connection with any standard rails and which will be equally applicable for use in connection with old or used rails as well as new stock.

The invention consists in certain novel features and combinations and arrangements involving particularly the entire plate and the means for supporting the wheels of rolling stock in such a manner that the strain is not imposed upon the extreme ends of the rails and which latter means may from time to time be replaced whenever the traffic causes undue or excessive wear in a manner as will be pointed out in the accompanying specification and claims.

In the accompanying drawings one complete example of the physical embodiment of the invention is illustrated, constructed and arranged according to the best mode so far devised for the practical application of the principles of the invention.

Figure 1 is a side view in elevation of my rail joint,

Fig. 2 is an enlarged cross section through a rail and showing the rail joint in elevation,

Fig. 3 is an enlarged cross section through the upper portion of the rail joint, and

Fig. 4 is a fragmentary enlarged detail in cross section showing the manner of securing the detachable shoe.

In the preferred embodiment of the invention as illustrated in the drawings, the ordinary type of rails 1 are shown in their true butted relation and joined therewith

by the rail joint of my construction illustrated at 2. This joint consists firstly of a tie plate member 3 which will rest upon at least two adjoining ties and provides a substantial rigid bed for the rail ends. Rising from the plate and adjustable to one side of the rail is the fish plate member 4 supporting the rail flange on the under side of the rail in the usual manner. Rising above this portion 4 is an extension 5 provided with a tongue lock construction 6 by which means a shoe 7 is supported on the rail joint in such a manner that replacement may be made from time to time as excessive wear upon the shoe 7 will necessitate. The shoe 7 is formed of approximately the same length as the rail joint and has its ends 8 beveled or sloping downward so that the extreme edges are slightly under the extreme top of the ball of the rail. At the center 9 of the joint and for some little distance either side thereof the shoe is slightly higher than the highest point of the ball of the rail and joins in a gradual curve or slope with the end portions 8. The shoe 7 which is here illustrated is provided on its under side with a groove 10 to fit closely and match with the tenon 11 supported upon the upper surface of the member 5. This groove is formed with a depending portion 12 closely engaging the top of the tenon so that a direct downward bearing surface may be had equal at least to the cross section of the shoe. To avoid compression and distortion upon the tenon space is provided on either side of the depending portion 12 so as to leave the tenon free from pressure over its weakest area over the undercut edges which will prevent distortion that would tend to weld or lock the shoe firmly to the upper end of the plate in such a manner as to prevent removal of the shoe when it is desired to replace with an unworn one.

Thus by reason of the above construction a dovetail lock is provided which will securely maintain the shoe upon the plate and prevent the same from lateral movement thereon and in addition has the advantages in providing bearing faces 12 and 13 which will constitute the entire cross section through the shoe and a longer life to the joint.

In combination with the joint 2 I provide and use the usual fish plate 14 which is com-

mon to the trade and provide in the plate 3 spike holes 15 so placed in the plate that they will correspond with the notches cut into the fish plate 14 for receiving the spikes. 5 When the bolts 16 have been passed through the joint plate 2 and the fish plate 14 and tightened up and the spikes have been driven into the ties through the holes 15 in the plate and through the notches 17 upon the 10 opposite edge of the plate, a firm and secure manner of fastening has been provided, the rail ends will be prevented against downward deflection by reason of weight passing over them, and the wheels will be prevented 15 from crossing the joint by reason of being lifted and slightly spaced therefrom by riding upon and over the shoe. This will prevent checking of the rails on the ends, of excessive wear at this point with consequent 20 crystallization and splintering, will render a longer life to the rails and will provide a joint which may readily be renewed or replaced as conditions demand with a minimum cost and the maximum of efficiency.

25 I claim:—

1. In a rail joint, a base plate, a fish plate rising from one side thereof and integral therewith, an upwardly extending longitudinal ridge on said fish plate, a shoe 30 removably supported thereon, said shoe being slightly higher than the ball of the rail at its center and inclining downward from

the center to each end, the extremities of which are lower than the ball of the rail.

2. In a rail joint, a base plate and a fish 35 plate integral therewith, an upwardly extending web portion formed on said fish plate and a tenon thereon, a shoe with a groove therein forming a dovetail with the tenon, a space between the shoe and the tenon, and a depending tongue engaging the tenon over the central portion thereof.

3. In a rail joint, a base plate and a fish 40 plate integral therewith, a shoe removably engaging with the fish plate and higher than the rail over its central portion and lower than the rail at its extremities, locking means for securing the shoe to the fish plate 45 consisting of a dovetail joint, and means whereby the shoe will engage the tenon of the dovetail on all surfaces except the upper 50 corners of said tenon.

4. In a rail joint, the combination of adjoining rail ends, a fish plate and a combination tie plate and fish plate, said latter 55 fish plate having an upraised edge portion adjusted closely alongside the outer side of the rails and supporting on its upper edge a shoe, said shoe removably attached to said upraised edge portion and having a direct 60 downward bearing surface equal to the cross section of said upraised portion.

In testimony whereof I affix my signature.
GEORGE LANCE.
